UNITED STATES PATENT OFFICE.

JOHN DANIEL MORARITY, OF TOPPENISH, WASHINGTON.

LOCK.

1,183,395.

Specification of Letters Patent.

Patented May 16, 1916.

Application filed January 16, 1915. Serial No. 2,717.

To all whom it may concern:

Be it known that I, JOHN D. MORARITY, a citizen of the United States of America and of the State of Washington, residing at 5 Tappennish, in the county of Yakima and State of Washington, have invented new and useful Improvements in Locks, of which the following is a specification.

The present invention relates to simple 10 and effective means for securely retaining the key in a lock or in the key hole of the escutcheon plate for the lock.

In carrying out my invention I propose to provide the escutcheon plate of the door 15 lock with a spring pressed sliding member that can be readily thrown into contact with the bit or key to prevent the removal of the key but at the same time may be readily actuated to permit of the withdrawal of the 20 key from the key hole opening in the escutcheon plate.

Another object of the invention is to provide a device of this character which will effectively sustain a key in a lock or which 25 will prevent its withdrawal through the key hole opening in the escutcheon plate, so that the necessity of constantly removing the key and the liability of the displacement of the said key will be obviated, and further to 30 obviate the necessity of the employment of extra bolts and catches upon a door, the key being always in position so that the door lock will serve the double purpose of both a catch and lock bolt.

With the above and other objects in view, 35 the improvement resides in the construction, combination and arrangement of parts set forth in the following specification and falling within the scope of the appended claim.

In the drawing: Figure 1 is an elevation 40 of a door provided with a mortise lock and illustrating by the dotted lines the position of my improvement upon the escutcheon plate therefor, Fig. 2 is a sectional view approximately on the line 2—2 of Fig. 1 showing 45 the plate engaging the key to sustain the same within the key hole opening in the escutcheon plate, Fig. 3 is a perspective view of the slideable plate, and Fig. 4 is a similar 50 view of the spring washer which co-acts with the latch plate.

Referring now to the drawings in detail 55 the numeral 1 designates a portion of a door having an ordinary mortise lock 2 inserted in an opening therein, and the sides of the door are provided with the ordinary es-

cutcheon plates 3 having key hole openings 4 which register with the key hole opening in the lock 2. The lock and escutcheon plates may be of any desired formation or 60 size, but the escutcheon plates are centrally embossed or in words have their face portions disposed beyond their edges, the said edges being flanged from the plates proper in the ordinary manner.

65

The numeral 5 designates the key catch, the same comprising a flat preferably rectangular plate 6 having a central elongated slot 7, and its upper edge is formed with an outturned flange portion 8 providing a 70 finger grip. The flange 8 is of a size sufficient to be received within the lower wall provided by the key hole opening 4 in the escutcheon plate 3 and rests upon the said wall but projects beyond the plate through 75 the opening.

The numeral 9 designates a metal washer, the same comprising a cup-shaped element and is formed of some suitable spring material. The flanged edges of the cup-shaped 80 washer 9 are slotted radially to provide spring fingers 10 and the said washer is centrally formed with a projecting stud 11 that passes through the slot 7 in the plate 5 and is secured upon the inner face of the es- 85 cutcheon plate 3. By such an arrangement it will be noted that the spring fingers 10 of the washer 9 contact with the sliding plate 5 to force the said plate 5 against the inner face of the escutcheon plate 3, and by grasping 90 the finger piece 8 the plate may be slid to the position illustrated in Fig. 2 of the drawings so that the same will contact with the bit of the key 12 and prevent the accidental withdrawal of the said key from the 95 key hole opening 4 in the escutcheon plate 3.

From the above description, taken in connection with the accompanying drawings, the simplicity of the device, as well as the advantages thereof will, it is thought, be 100 perfectly apparent to those skilled in the art to which such invention appertains without further detailed description.

Having thus described the invention, what I claim is:

105

In a device for the purpose set forth, the combination with a lock escutcheon plate having a key opening, of a flat slideable plate arranged upon the inner face of the escutcheon plate, said flat plate having its 110 upper edge centrally provided with a laterally extending reduced member which

passes through the key hole opening and normally rest upon the lower wall provided thereby, the said plate being provided with a centrally disposed elongated opening, a cup-shaped metal washer having peripheral slits forming spring fingers bearing against the plate, and a stud centrally connected with the washer and passing through the

elongated opening in the slideable plate and secured to the escutcheon plate. ¹⁰

In testimony whereof I affix my signature in presence of two witnesses.

JOHN DANIEL MORARITY.

Witnesses:

J. H. IMMEL,
J. W. WARRELL.
